Primary Examiner — Omeed Agilee*Assistant Examiner* — David Truong(74) *Attorney, Agent, or Firm* — Bridgeway IP Law Group, PLLC; Sang Ho Lee; Hyun Woo Shin(57) **CLAIM**

The ornamental design for a packaging container as shown and described.

DESCRIPTION

FIG. 1 is a perspective view of a packaging container, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an enlarged view of portion 8 shown in FIG. 1. The broken lines in the drawings show portions of the packaging container, which form no part of the claimed design.

1 Claim, 7 Drawing Sheets(56)
